DESIGN FOR AN ASH TRAY

Bill J. Potter, Fort Worth, Tex.

Application June 17, 1946, Serial No. 130,821

Term of patent 14 years

(Cl. D85—2)

To all whom it may concern:

Be it known that I, Bill J. Potter, a citizen of the United States, residing at Fort Worth, in the county of Tarrant and State of Texas, have invented a new, original, and ornamental Design for an Ash Tray, of which the following is a specification, reference being had to the accompanying drawing, forming a part thereof.

Figure 1 is a perspective view of an ash tray, showing my new design.

Figure 2 is a vertical sectional view taken on lines 2—2 of Figure 1.

I claim:

The ornamental design for an ash tray, substantially as shown.

BILL J. POTTER.
